[57] CLAIM

The ornamental design for a fluid-powered hand punch,
substantially as shown and described.

DESCRIPTION

FIG. 1 is a perspective view of the fluid-powered hand
punch showing my new design with the power cord
shown broken away to depict indeterminate length;
FIG. 2 is an enlarged rear elevational view thereof;
FIG. 3 is an enlarged end elevational view thereof;
FIG. 4 is an enlarged front elevational view thereof;
FIG. 5 is an enlarged side elevational view thereof, the
opposite side being a mirror image.

FIG. 2

FIG. 1

FIG. 3

FIG. 4

FIG. 5
